United States Patent Office

Des. 205,976
Patented Oct. 11, 1966

205,976

WINDOW DISPLAY STAND

Michael Emhoff, 1480 Ocean Ave., Brooklyn, N.Y.

Filed Jan. 14, 1966, Ser. No. 1,273

Term of patent 14 years

(Cl. D80—9)

FIG. 1

FIG.3

FIG. 1, a front elevation of a window display stand illustrating my new design;

FIG. 2, a top plan view thereof;

FIG. 3 is a rear elevational view thereof; and

FIG. 4 is an elevational view taken from the right side of FIG. 1.

This is a continuation-in-part of Design application Serial No. D.83,661, filed February 2, 1965, now abandoned.

I claim:

The ornamental design for a window display stand, as shown and described.
